PROJECTING DEVICE

Felix Tarullo, Southbridge, Mass.

Application November 7, 1939, Serial No. 303,282

5 Claims. (CL. 88—24)

My invention relates to improvements in projecting devices for use in photography, and its primary object is provision of a device of this character which is simple and rugged in construction and can be easily adjusted to perform different operations in connection with photographic enlarging, reducing and copying.

Other important objects and advantages of my invention will be apparent from a reading of the following description and the drawings wherein a preferred embodiment of my invention is set forth for illustrative purposes.

In the drawings—

Figure 1 is a side elevational view of the embodiment having a conventional enlarging camera associated therewith.

Figure 2 is a fragmentary transverse vertical sectional view taken through Figure 1.

Figure 3 is a horizontal sectional view taken through Figure 1 approximately on the line 3—3 and looking downwardly in the direction of the arrow.

Figure 4 is a fragmentary view similar to Figure 3 but showing the special copying and projecting holder in place.

Figure 5 is a side or edge elevational view of the special copying and projecting holder slide.

Figure 6 is a top or bottom plan view of the holder of Figure 5.

Figure 7 is a top plan view of Figure 5.

Figure 8 is an end elevational view of Figure 5.

Figure 9 is a side elevational view showing the head reversed from the position shown in Figure 1 and having mounted thereon a printing head.

Figure 10 is a detail sectional view through a portion of the housing and showing how a holder is held therein.

Referring in detail to the drawings, the numeral 5 generally designates a suitable pedestal including the feet 6 and the tubular standard 7 rising therefrom and having vertically slideable thereon the open-work sleeve 8 to the upper part of which is attached a horizontally extending daddy-long-legs 9 terminating in a vertical bar 10 whose upper end is swivelly connected at 11 to one side of the cylindrical housing 12. The bar 10 has a vertical slot 13 in its lower end for pivotal and sliding engagement with the pin 14 on the lower end of the adjacent link of the extensible member 9. For printing operations the sleeve 8 may be reversed in position on the standard 7 as shown in Figure 9 wherein the cylindrical housing 12 is similarly reversed. A cable 15 has one end connected at 16 to the

member 8 and is trained over a pulley 17 supported on the upper end of the standard 7 through which the remaining end of the cable depends and is attached to a weight 18 which counterbalances the extensible member 9 and its burden. A fixed bracket 19 on an intermediate part of the standard 7 has a crankhandle 20 mounted therein in operative relation to a screw 21 which is engaged to operate the slidable bracket 22 which supports the easel 23 at the required distance below the camera 49 or other instrumentality positioned above it.

The cylindrical housing 12 has mounted on its top the porcelainized dome 24, the connection 15 25 therebetween being annularly grooved as indicated at 26 to support the opal glass 27. The top of the dome terminates in an axial cupola 28 through which supportably extends a conduit 29 for energizing and supporting a cluster 30 of suitable electric lights.

The interior of the cylinder 12 has a step-cut annulus 31, acting as a plate or paper holder, 20 25 removably resting on spaced lugs 32 positioned slightly below the upper end of the housing as shown in Figure 2.

The bottom of the housing 12 is open, the bottom edge thereof having abutted thereto the radial horizontal flange 33 on the annulus 34 which removably surrounds the lower end of the housing and is held in place by studs 35 engaging bayonet slots 35'. The flange 33 acts as a retainer for the holder assembly which comprises the annular pan-shape 36 which has a square opening 37 formed through its center and coaxial with the cylindrical housing 12. The pan-shape 36 has four similar slots 38 distributed uniformly on four opposite sides thereof, through which the adjustable slides 39 extend to enable modifying the size of the opening 37. The slides have handles 40. On two opposite sides of the housing 12 motion picture film reels 41 and 42 are mounted on the outside of the housing to feed motion picture through accommodating slots 43 formed in the sides of the housing so that the film may extend across the opening 37, whereby downward projection of the film is provided for.

Electric lights 44 (for use only with the special holder to be described) are horizontally positioned as indicated in Figures 2, 3 and 4 circumferentially around the top of the pan-shape 36, with suitable insulated conductors 45 leading thereto from outside of the housing 12.

The pan-shape 36 has depending from the 55 bottom thereof two L-shaped enlarging camera

slides 46 and 47 between the edges of the opening 37 and the sides of the housing 12 to receive the upper part 48 of the enlarging camera 49 having the opening 49', as shown in Figures 1, 2 and 4.

The glass 53 rests in the special holder 55 thereby supporting the picture 51 on which rests the metal sheet 54. The special holder 55 fits in the special slide 58, the latter consisting of a circular metal plate 57 having depending diametrically opposed laterally slotted lugs 58 and 59 and diametrically disposed blocks 60 and 61 between them. Fixed on the top of the plate 57 along the longitudinal edges of the elongated opening 62 are the holder receiving brackets 63 and 64 which are reinforced by respective braces 65 and 66. The ends of the opening 62 have angulated corners as indicated at 67. As shown in Figure 10, the holder 55 is mounted in the housing 12 by a pair of diametrically opposed bolts provided on their radially inward ends with wing nuts 71 and 72 thereon to bear against the inner sides of the lugs 58 and 59, respectively, with the slots of these lugs engaging the shanks of the bolts.

In Figure 9 is shown an ordinary printing box arrangement 68 connected by means of the camera connector slides 46 and 47 to the cylindrical housing 12 with the latter in an inverted position instead of its usual erect position.

Although I have shown and described herein a preferred embodiment of my invention, it is to be definitely understood that I do not wish to limit the application of my invention thereto except as may be required by the scope of the subjoined claims.

Having described the invention, which is claimed as new is:

1. Apparatus of the character described, said apparatus comprising a support, a vertical substantially cylindrical main housing mounted on one side of said support, a lamp housing mounted on the upper end of said cylindrical main housing, a main holder separably connected to the lower end of said main housing, said main holder having depending means enabling connection of an enlarging camera, means mounting said main housing on said support and enabling reversing said main housing to position said main holder above said main housing, and a printing box mounted on and above said main housing by means of said depending means.

2. Apparatus of the character described, said apparatus comprising a support, a vertical substantially cylindrical main housing mounted at one side of said support, a lamp housing mounted on the upper end of said cylindrical main housing, a main holder separably connected to the lower end of said main housing, said main holder having depending lugs enabling connection of an enlarging camera, said main holder comprising a circular plate from which said lugs depend and upstanding parallel longitudinal retainers ranged on opposite sides of an elongated opening formed

in said plate, and a frame slidably mounted on said plate in engagement with said retainers.

3. Apparatus of the character described, said apparatus comprising a support, a vertical main housing mounted at one side of said support, a lamp housing mounted on the upper end of said main housing, a main holder separably connected to the lower end of said main housing, said main holder being formed with a centralized opening, said main holder having depending means for connection of an enlarging camera, said main holder comprising a portion telescoping into the lower end of said main housing, and a retainer, said retainer comprising a frame surrounding the lower part of said main housing, said frame having an inwardly extending flange projecting under said main housing to supportably engage the bottom of said portion of the main holder, and releasable means securing said frame in place.

4. Apparatus of the character described, said apparatus comprising a support, a vertical main housing mounted at one side of said support, a lamp housing mounted on the upper end of said main housing, a main holder separably connected to the lower end of said main housing, said main holder being formed with a centralized opening, said main holder having depending means for connection of an enlarging camera, said main holder comprising a portion telescoping into the lower end of said main housing, and a retainer, said retainer comprising a frame surrounding the lower part of said main housing, said frame having an inwardly extending flange projecting under said main housing to supportably engage the bottom of said portion of the main holder, and releasable means securing said frame in place, the said lower part of the main housing and said frame being circular in form, and said releasable means comprising bayonet and bayonet slot means.

5. Apparatus of the character described, said apparatus comprising a support, a vertical main housing mounted at one side of said support, a lamp housing mounted on the upper end of said main housing, a main holder separably connected to the lower end of said main housing, said main holder being formed with a centralized opening, said main holder having depending means for connection of an enlarging camera, said main holder comprising a portion telescoping into the lower end of said main housing, and a retainer, said retainer comprising a frame surrounding the lower part of said main housing, said frame having an inwardly extending flange projecting under said main housing to supportably engage the bottom of said portion of the main holder, and releasable means securing said frame in place, said main holder being formed with a centralized opening, adjustable horizontal masking slides mounted in slats formed in said main holder for selectively masking said opening, the radially outward part of said slides passing through slats formed in said frame.

FELIX TARULLO.
